UNITED STATES PATENT OFFICE.

ELMER C. SALLWASSER, OF BERWYN, ILLINOIS, ASSIGNOR OF ONE-THIRD TO
BERNARD J. PALCZYNKI, OF CHICAGO, ILLINOIS.

ATTACHMENT FOR RADIO RECEIVING SETS.

Application filed July 22, 1922. Serial No. 576,661.

This invention relates to radio receiving apparatus and has for its principal object to permit the use of a plurality of head sets of other telephones with a single receiving set and to make it possible to locate the head sets or the like at any suitable place within a reasonable range from the relatively fixed receiving apparatus proper.

Further objects of the invention will become apparent as the description is read in connection with the accompanying drawing illustrating a selected embodiment of the invention, and in which

Fig. 1 is a plan view of a terminal base 10 adapted to receive a plurality of head sets and be connected with the receiving set;

Fig. 2 is an inverted plan view looking at the bottom of Fig. 1;

Fig. 3 is a transverse section of the terminal base;

Fig. 4 is a diagrammatic view showing how the base with a plurality of telephones is connected with the terminals of a receiving set; and

Fig. 5 is a similar view showing a plug and jack connection between the cables and the receiving set.

Radio receiving sets in common use at the present are generally equipped with a single head set or the like which is connected by short wires or cables with the receiving set. As a result only one person can listen to the concerts or the like at a time and that person must remain in proximity to the receiving set. By an attachment made according to my invention, a plurality of head sets or the like may be connected with a receiving set and may be located at any suitable place within convenient range of the receiving set. For example: if the receiving set is in a down stairs living room, the head sets may be on the porch, in an upstairs living room, or other place.

I accomplish this by providing a terminal base 10 equipped with a plurality of means for receiving head sets or the like and connected by suitable cables 11 with a receiving set 12. As shown, the terminal base includes a block of insulating material 14 having secured to its upper surface a pair of metal bars 15 by means of screws 16 and 17 which pass through the bars and the block and receive nuts 18 and 19 located within suitable sockets 20 and 21 in the bottom of

the block. The screws 17 are elongated as indicated at 22 and receive additional nuts 23 by which the cables 11 are connected with the bars. Each of the bars is provided with a plurality of openings 24 to receive the cables of head sets or the like which are secured within the openings by means of thumb screws 25 extending transversely thereto. In the construction here illustrated provision is made for five head sets 60 which will be sufficient for the average requirement and which is about as large a number as can be used without supplying additional power.

The cables 11 may be fitted with suitable 70 connections 26 for cooperation with terminals 27 as shown in Fig. 4 or they may be attached to a plug 28 adapted to cooperate with the jacks 29 as shown in Fig. 5. The cables are easily attached to and detached 75 from both the terminal base and the head set and that makes it possible to provide a series of selective cable sets that will permit the terminal base with its plurality of telephones to be located close to the receiving 80 set as is customary at the present time, or in a distant room, on a porch or lawn, or other suitable place at a distance from the receiving set. Ordinarily the cables will remain connected with the terminal base which 85 will be moved about from place to place as occasion may require, but it will be possible to substitute for the cables permanently installed wiring leading to selected locations to which the terminal base may be 90 connected and disconnected as desired.

While the device is primarily intended for use with a plurality of head sets, it will be clear that it may also be used with equal advantage with other forms of telephones. 95

The invention permits a number of persons to listen to the radio communications at once and makes it possible for them to select their locations with regard to personal comfort and to move from one place to 100 another while the receiving set remains stationary.

I am aware that changes may be made in the form, construction and arrangement of the invention, as set forth in the selected embodiment herein, without departing from the scope or sacrificing any of its material advantages, and I therefore reserve the right to make all such changes as fairly fall within the scope of the following claim. 110

I claim:

Means for connecting up a series of head sets, comprising a block of insulating material, a pair of members, means for securing said members to the said block, the block being provided with sockets upon its under face, the securing means for said members being passed through the latter and the block and into said sockets, means

on said securing means disposed in said 10 sockets for connection of cables, the said members being provided with holes for the reception of the cables of head sets, and means cooperating with said holes for securing the last-named cables removably in 15 place.

ELMER C. SALLWASSER.
